UNITED STATES PATENT OFFICE

1,932,554

GREENHOUSE ROOF SUPPORT

Philip L. McKee, Pana, Ill.

Application June 5, 1931. Serial No. 542,256

7 Claims. (Cl. 189—4)

This invention relates to greenhouse roof supports, and the primary object of the invention is to provide a new and improved roof support having a gutter provided therein, the roof support being made in sections and spliced in a particular manner so that it is impossible for any water carried by the gutters or drains in the supports to seep into the splice and cause deterioration of the roof support at the splice.

10 A further object is to provide a roof support or rafter having a drain provided therein, which support or rafter is capable of being made in sections and splicing the various sections together, the splice being made so that the water 15 draining from one part of the rafter will not seep into the splice and cause deterioration of the rafter at the splice.

A further object of the invention is to provide a jointed roof support whereby a particular splice 20 is made at the joints to prevent water carried by the support from seeping into the joint, and whereby sections between joints can be made of different dimensions and thickness and still permit the water carried in gutters provided in the 25 roof members to drain off properly.

Numerous other objects and advantages will be apparent throughout the progress of the following specification.

The accompanying drawing illustrates a selected embodiment of the invention and the views therein are as follows:

Fig. 1 is a detail sectional view of a greenhouse and embodying the invention.

Fig. 2 is a detail sectional view of a roof support or rafter and having the invention applied thereto.

Fig. 3 is a detail sectional view on the line 3—3 of Fig. 2.

Fig. 4 is a view similar to Fig. 2 showing the rafter made in sections of different sizes and showing the manner in which the rafters are supported by the side walls of the greenhouse and by intermediate supports arranged at the joints or splices.

45 Referring to the drawing, 5 designates a greenhouse which is preferably constructed in accordance with the greenhouse disclosed and claimed in the copending application, Serial No. 542,756, filed June 8, 1931, and allowed February 13, 1933.

50 The greenhouse has roof supports 6 which have their upper ends supported and operatively connected to a longitudinal ridge bar 7. The roof supports or rafters 6 are preferably made in a plurality of sections as indicated by the numerals 8. The sections may be spliced together

at various places as indicated at 9. The lower ends of the supports or rafters 6 are supported by the foundation walls 10 of the greenhouse, and intermediate supports or columns 11 may be positioned at suitable intervals, if required, 60 and particularly if the greenhouse is relatively wide.

The upper ends of the rafters 6 are fitted to the longitudinal ridge bar as indicated at 12, Fig. 2, and a cap 13 is provided over the top of the ridge bar to prevent water from entering the joint 12. A bottom plate 14 may also be provided and secured to the rafters 6 and the ridge bar 7 for the purpose of holding these members in position and adding rigidity thereto.

The supports or rafters 6 have outwardly extending ledges 15, Fig. 3, to support the glass 16. The rafters may be shaped inwardly as designated at 17 to provide a gutter 18 to drain off any water which may come in contact with the rafters. A ledge 19 projects upwardly from the widened or flanged bottom portion 20 of the rafters for the purpose of making the gutters relatively deep.

It is impracticable and sometimes utterly impossible to make the rafters in one piece, particularly in connection with an offset roof as shown in Fig. 1. Also, it adds considerably to the cost of the rafters if they are made in one piece. Therefore it is desirable, both from an economical standpoint in construction and also in shipping, that the rafters be made in a plurality of sections. Difficulty has been encountered heretofore in providing a joint between the various sections as the water in the gutters would get into the joint or splice and cause rapid deterioration of the rafters at the joints. The present invention overcomes these disadvantages by providing a new and novel joint whereby it is impossible for the water which drains from one section to another section to get into the joint or splice. The splice consists in varying the location of the gutter in one section relative to the gutter in its companion or adjacent section, and also by having the gutter in the upper section rabbeted below the gutter in that section for the purpose of receiving a tongue provided in the lower companion section.

In Fig. 2 the rafter 6 shows a pair of sections 8 which are the same size in cross-section, thereby making the tops and bottoms of each section flush. However, in the upper section the gutter is located a distance above the base, while the gutter 18 in the lower section is relatively closer to the bottom as shown in Fig. 2. Thus, water passing down the gutter in the top section

8 will drop into the gutter in the lower section. However, if the splice, as indicated by the numeral 21, were cut straight across, the draining water would enter the splice. The upper section 8 is 5 rabbeted as indicated at 21 to receive the projecting tongue 22 on the lower adjacent section. Thus, any water passing down the gutter in the upper section will flow directly into the gutter in the lower section, it being impossible for the 10 water to find its way into the joints which are indicated by the numerals 23.

In order to brace the rafters at the splices 23, front to rear supports 24 may be provided. These supports are preferably made of ordinary metal 15 pipe and are supported by straps 25 which may be held in position by screws 26 engaging the wooden sections. It is preferable, however, that a plate 27 be interposed between the upper side of the pipe and the bottom of the rafters for the 20 purpose of providing strengthening means at the joint or splice. Also, if desired, an outer plate 28 may be connected to adjoining rafters as shown in Fig. 2. The longitudinal pipes 24 may carry fittings 29 at certain intervals which 25 fittingly receive the upper ends of the supporting columns 11. Each fitting 29 may be spliced as indicated at 30 and the parts held together by a bolt and nut connection 31.

In Fig. 4 an upper section 8 is smaller in cross-sectional area than its cooperating adjacent lower section 8'. In this latter embodiment the section 8 is rabbeted at 32 to receive a tongue 33 on the section 8', the splice having an inclined edge 34 so that the bottoms of each section will be even as well as the tops thereof. However, these sections may be reversed so that the larger heavier section is above the lower section, if desired. However, regardless of the positioning of these sections, the gutter 18 in the upper section must be located above the gutter 18' in the lower section so that water carried by the upper section will flow into the gutter of the lower section.

The usual front to rear pipe supports 24 may 45 be supported in position as previously described relative to Fig. 3 and are supported by the columns or supports 11. The lower ends of the bottom sections 8 or 8' are supported and fixed to a cap 35 which is carried by the side walls 50 10. Upper and lower angle braces 36 and 37 respectively are fastened to the sections and to the cap as shown in Fig. 4.

The invention provides a new and novel greenhouse construction in which the roof supports 55 or rafters are made in sections and spliced together, each section carrying a gutter, the upper gutters in the upper sections, however, being located above the gutters in the lower sections so that water carried by these gutters will 60 drain down to the sides of the building and not enter the splices and cause deterioration of the rafters at the splices. A greenhouse constructed in accordance with the invention can be made considerably cheaper than conventional greenhouses and the particular splice construction 65 employed prevents water carried by the rafters from getting into the joints or splices and causing deterioration of the rafters as well as preventing water from dripping down into the greenhouse.

Changes may be made in the form, construction, and arrangement of the parts without departing from the spirit of the invention or sacrificing any of its advantages, and the right is hereby reserved to make all such changes as

fairly fall within the scope of the following claims.

The invention is hereby claimed as follows:

1. A roof support for greenhouses comprising a member having a longitudinal groove therein and providing a gutter, a second member spliced to said first member and having a gutter lying in a plane which is below the first gutter whereby a vertically offset drain is provided for the roof support, said second gutter lying in the same vertical plane as the upper gutter. 80 85

2. A roof support comprising a plurality of members spliced together, an upper adjacent member having a cut-out therein for receiving a tongue on a lower adjacent member, each of said members provided with gutters formed in opposite sides thereof, the gutters in an upper member being located in a plane above the gutters in a lower adjacent member whereby an offset gutter is provided for the roof support, permitting water in an upper gutter to drain into the lower gutter. 90 95

3. A roof support comprising a pair of members spliced together, one member being located above another member, a longitudinal gutter 100 formed in the upper member and located a predetermined distance from the bottom of said member, said member having an end rabbeted at a point below the gutter, said second member having a gutter located a certain distance above the bottom, said distance being less than the distance between the first named gutter and the bottom of said first named member, a tongue on said second member and engaging the rabbet in the first named member, said tongue having a gutter 105 coextensive with the gutter in the second member and extending beyond the gutter in the end of the first member whereby water carried by the gutter in the first member will drop into the gutter in the second member and be prevented 110 from entering the joint between said two members. 115

4. A roof support comprising a member having a bottom ledge, said ledge being grooved to form a gutter, a second member adjacent said first named member and also having a bottom ledge, the ledge on said second member being narrower than the ledge on the first member, said ledge on the second member also provided with a groove therein forming a gutter, the ledge on the second member extending into the ledge in the first member but below the gutter in the first member whereby water in the first named gutter will drop down into the gutter in the second member. 120 125 130

5. A spliced roof support comprising a pair of roof members spliced together, each of said members having lower side ledges, the ledges of one member being narrower than the ledges of the other member, grooves in both of said ledges and forming offset gutters arranged one above the other whereby water carried by the gutter in one ledge will drain into the gutter in the narrower ledge. 135 140

6. A spliced roof support comprising a plurality of roof bar members of different cross-sectional area, said members being located at an angle and spliced together, said splice being constructed and arranged so that the tops and bottoms of said members will be flush, gutters formed in both of said members, the gutter of one member being located above the gutter in the other member and extending a certain distance beyond the end of said other gutter whereby water carried by the 145 150

gutter in the first member will drain into the gutter in the second member.

7. A spliced roof bar construction for a greenhouse roof comprising two roof bars spliced together and lying at a downward inclination with respect to the horizontal, each of said bars having

a vertical side ledge, there being grooves formed in said ledges and providing gutters, the ledge of one bar being smaller in dimension than the ledge of the other bar, the gutter in one bar draining in the gutter in the other bar.
